UNITED STATES PATENT OFFICE.

ALBERT C. ELLITHORPE, OF CHICAGO, ILLINOIS.

FIRE-ESCAPE.

SPECIFICATION forming part of Letters Patent No. 277,891, dated May 22, 1883.

Application filed February 15, 1883. (No model.)

To all whom it may concern:

Be it known that I, ALBERT C. ELLITHORPE, of Chicago, in the county of Cook and State of Illinois, have invented certain new and useful 5 Improvements in Fire-Escapes; and I do hereby declare that the following is a full, clear, and exact description of the invention, which will enable others skilled in the art to which it appertains to make and use the same, reference 10 being had to the accompanying drawings, and to letters of reference marked thereon, which form a part of this specification.

The object of my invention is to provide an easy and perfectly-safe means of exit from 15 burning buildings, which will, after having easily lowered the person to the ground and is relieved of his weight, automatically return to its first or normal position. This is accomplished by a device which utilizes atmospheric 20 resistance and vacuum, consisting of an air-tight cylinder, in the heads of which a shaft is journaled, and between which the same is screw-threaded, so that when the shaft revolves by reason of the unwinding of the escape-rope 25 a diaphragm in the cylinder, which is tapped to receive the threaded part of said shaft, will be moved from one end to the other of said cylinder, creating a vacuum on its receding side and compressing the air on its advancing side, thus acting as a brake to the 30 shaft, permitting it to revolve to unwind the escape-rope only as the compressed air on the advancing side of the diaphragm can escape to partially fill the vacuum created on the receding side of the same. When the escape-rope 35 has reached the ground and is relieved of its load the back-pressure of the compressed air on the diaphragm and the tendency of a weighted rope to unwind will reverse the motion of 40 the shaft, thus opening valves in the diaphragm to equalize the air on either side of the same, and restoring the device to its normal position.

In the drawings, Figure 1 is a vertical longitudinal section, and Fig. 2 is a front elevation.

In the drawings, A represents an air-tight cylinder, in the heads *a a* of which is journaled the shaft B, passing centrally and longitudinally through the same.

On one end of the shaft B is placed a drum, C, of suitable diameter, around which is wound

the escape-rope b, and on the other end of said shaft is a drum, D, smaller in diameter than drum C, around which the weighted rope d is wound in a direction contrary to that of the escape-rope. Thus when the escape-rope is wound on its drum the weighted rope will be unwound, and vice versa. The shaft B between the heads *a a* of the cylinder is screw-threaded, and passes through the tapped perforation of 55 the diaphragm E in the cylinder, the periphery of said diaphragm fitting snugly against the annular surfaces of the same. This diaphragm E is prevented from revolving with the shaft by one or more guide-rods, e, which are placed longitudinally and are secured in the heads of the cylinder and pass through suitable perforations in said diaphragm, near its periphery. When, therefore, the shaft revolves so as to unwind the escape-rope from the drum the diaphragm, 60 which in its first position will be near the head of the cylinder farthest from the escape-rope, will be moved toward it, rarefying the air on its receding side and compressing the air before it, thus retarding the forward movement 65 of said diaphragm according as the compressed air can escape into the vacuum to increase its expansibility. This action of the air in the cylinder on the diaphragm makes it act as a brake on the shaft, permitting it to revolve 70 just so fast, or at a safe rate of speed, lowering the person having hold of or attached to the escape-rope carefully to the ground. When the escape-rope is relieved of its load the compressed air in front of the diaphragm, the rarefied air back of it, and the tendency of the weighted rope d to unwind combine to reverse 75 the motion of the shaft and return the diaphragm to its original position. This backward movement of the diaphragm is materially 80 assisted, when it has reached that point in the cylinder where the consistency of the air on either side of it is about equal, by the opening of one or more valves, g g, in the diaphragm, thus avoiding the resistance from atmospheric 85 pressure it might otherwise experience. When the escape-rope is rewound on the drum the diaphragm will have returned to its first or normal position, and the device will be ready for another trip.

To prevent the shaft from moving longitudinally I place collars on it flush against the boss

of the heads of the cylinder; but this can be accomplished just as well and more economically by placing the drums on either end of the shaft flush against the said bosses.

5 If desired, and in order to avoid any possibility of a sudden precipitation to the ground when a person is being lowered, I place a spring, G, on the inside of the head *a* nearest the escape-rope drum, of any suitable construction, 10 which acts as a cushion, against which the diaphragm will bear when the escape-rope has unwound and reached, say, within six feet of the ground. This would avoid the possibility of a sudden shock when striking the ground.

15 If desired, the weight attached to the end of the rope *d* may be placed in a vertical cylinder its peripheries fitting snugly against the annular circumference of said cylinder, so that it will compress the air in the cylinder as it is raised, 20 thus furnishing extra resistance to the revolutions of the shafts as the escape-rope is being unwound. In this event the weight would be provided with valves similar to those in the diaphragm, so that as the weight is lowered 25 it will experience no opposition from atmospheric pressure, the whole of which is shown in Fig. 1.

30 I do not consider it beyond the scope of my invention if two diaphragms are used instead of one, in which case the shaft would have a right and a left screw-thread, commencing from the center of length of the same. The diaphragms would move in opposite directions from the center of length of the cylinder toward the ends of the same when the escape-rope was 35 unwinding, and then from the ends to the center of the cylinder when said rope was being rewound. When there are two diaphragms acting in the above manner it is obvious the resistance of the vacuum created 40 between the two would be sufficient of itself to accomplish the object of my invention, and the cylinder-heads may be of open-work only, adapted to furnish bearings for the shaft.

45 It will be understood that the pitch of the screw-threaded part of the shaft and the length of the escape-rope will be regulated according

to the altitude of the device, or, in other words, the distance to be traveled to reach the ground.

50 My invention may be placed above or below the window, or in any suitable position on the outside of a building, and it may be made more ornamental than reference to the drawings might suggest. It may also be used in commercial houses for lowering goods, being much safer in handling than the ordinary rope and pulley now in common use.

55 It will be seen from the above that I do not confine myself to a double-headed cylinder, as, if desired, the machine may be operated either 60 with a vacuum or by atmospheric resistance.

What I claim as new, and desire to secure by Letters Patent, is—

1. An automatic and pneumatic fire-escape 65 consisting of an air-tight cylinder, a shaft running centrally and longitudinally through the same, which is screw-threaded within and between the heads thereof, and a non-revolving diaphragm within said cylinder, tapped to receive said shaft, which, as the shaft revolves, 70 is moved from one end of the cylinder to the other, creating a vacuum on its receding side and compressing the air before it, thus retarding its too rapid movement forward and controlling the revolutions of the shaft. 75

2. The combination of a shaft passing longitudinally and centrally through an air-tight cylinder, and screw-threaded between the heads thereof, a weighted rope wound around the end of said shaft, and a diaphragm within 80 said cylinder which moves longitudinally, and is tapped to receive said shaft, as hereinbefore described.

3. The combination of the cylinder, the shaft, one or two diaphragms having valves, 85 the escape-rope, and the weighted rope, substantially as set forth.

In testimony that I claim the foregoing as my own I hereunto affix my signature in presence of two witnesses.

ALBERT C. ELLITHORPE.
